[57] CLAIM

The ornamental design for a housing for a cellular base unit, as shown and described.

DESCRIPTION

FIG. 1 is a top, right, and front perspective view of a housing for a cellular base unit showing my new design, the broken line showing being for illustrative purposes only and forming no part of the claimed design;

FIG. 2 is a bottom plan view of the housing of FIG. 1;
 FIG. 3 is a rear elevational view of the housing of FIG. 1;
 FIG. 4 is a left side view of the housing of FIG. 1, the broken line showing being for illustrative purposes only and forming no part of the claimed design; and,

FIG. 5 is a top, right, and front perspective view of a second embodiment of that shown in FIG. 1, the only difference being that the broken line showings of the first embodiment are shown in solid claimed lines in the second embodiment.
